UNITED STATES PATENT OFFICE.

MAURICE ALLAND, OF ATLANTIC CITY, NEW JERSEY.

PENCIL AND ERASER THEREFOR.

Application filed November 14, 1925. Serial No. 68,951.

The object of the invention is to provide improvements in pencils and particularly in the erasers with which the average pencils are equipped.

5 The usual pencil has but a single lead and also a single piece of rubber, or similar material, which serves while it lasts as means for removing or erasing marks made by the lead upon paper or the like. In practice it 10 seems that the pencil manufacturers have endeavored to arrive at, and attach to a pencil, a size of eraser which will last throughout the use of the major portion of the lead in the pencil, and will leave little or none of the 15 rubber to be thrown away when the lead is gone. As a result for many pencil users the amount of rubber supplied with a new pencil is not sufficient to last throughout the life of the lead and as a result during the final 20 stages in the use of the lead, frequently as much as half of said lead is not accompanied by the presence of any eraser whatever.

Therefore, another object is to provide a much larger piece of rubber than is usually 25 supplied with a pencil, but to so construct the eraser supporting structure as to expose only the desired amount of rubber at a time.

A further object is to provide this more 30 extensive eraser for magazine pencils, in which a large number of leads is adapted to be carried, and particularly in which case the usual eraser would be far from sufficient to supply even the average demand. In this 35 instance, the eraser serves the additional purpose of forming a closure, or stopper, for the magazine in which the reserve supply of leads is kept.

And still another object is to provide a most 40 simple construction for supporting and exposing the eraser by degrees as its outer portion is worn away by constant usage, said construction comprising a ferrule rotatably supported in threaded engagement upon the body of the pencil, and through the outer 45 open end of which normally protrudes the serviceable end portion of the eraser, said ferrule also being operative when rotated outwardly to entirely cover the sides and protect the eraser against injury, or becoming 50 dirty, when not in use.

Further details in the construction and operation of the invention are fully brought out in the following description, when read in conjunction with the accompanying drawings, 55 in which Fig. 1 is a side elevation of one embodiment of the invention; Fig. 2 is a longi-

tudinal section of a fragmentary portion of the device taken on the line 2—2 of Fig. 1; Fig. 3 is a section on the line 3—3 of Fig. 2; and Fig. 4 is a section on the line 4—4 of Fig. 2.

Referring to the drawings, a magazine pencil is represented as comprising a body 1, having a tapered end portion 2, through which protrudes a writing lead 3, adapted to be replaced and adjustably positioned by any suitable type of mechanism (not illustrated in detail). The body portion 1 at the end opposite to the lead 3 comprises a shell 4, within which is centrally positioned a casing 5 which incloses the lead-positioning mechanism, said casing and the surrounding shell being in uniform spaced relation, to provide a substantially cylindrical chamber 6 in which reserve leads 7 may be positioned or stored, and from which such leads may be removed as they are required, for replacing the lead in operative position in the opposite end 2.

The shell 4 terminates in an externally threaded open end 8, into which normally 80 extends a reduced end portion 9 of an eraser, the body portion 10 of which extends freely therefrom and provides an exposed end portion 11, adapted to be employed for removing lead marks from paper or the like in the usual manner. A ferrule, having an internally threaded body portion 12, normally in threaded engagement with the correspondingly threaded portion 8 of the shell 4, comprises a relatively short, smooth-bored end 90 portion 13 surrounding the body 10 of the eraser, and a relatively longer, smooth-bored portion 14 extending slidably over the adjacent end portion of said shell, so as to protect the threaded portion 8, to form an attractive 95 adjustable covering for the magazine portion of the instrument, and to form a suitable support for any desired type of clip 15 employed to removably attach the said instrument to one's pocket, or the like.

In using this improved writing instrument, the pencil is manipulated in the usual manner to withdraw or expose the lead 3 as desired.

When necessary to replace a worn lead by a fresh one, or to substitute for one lead a second lead of a different color, the ferrule 12 is rotated outwardly until it is entirely free of the threaded portion 8 and can be removed from the eraser 10. The eraser itself is then 110 removed from the chamber 6 so as to expose the reserve leads in the latter. The proper

lead can then be removed and inserted in the opposite tapering end portion 2 of the pencil, after which the said eraser is replaced as a stopper for the storage chamber, and the ferrule 12 is replaced as shown in the drawings. Also, as the exposed end portion 11 of the eraser becomes worn away, this ferrule is rotated inwardly further and further upon the threaded portion 8 of the shell, in order 10 to correspondingly expose more and more of the body 10 of the otherwise protected portion of the rubber.

Having thus described my invention, what I claim and desire to protect by Letters Patent of the United States is:—

An instrument of the class described comprising a hollow container body provided with exterior screw threads adjacent one end

thereof, an eraser removably closing the body at said end, a ferrule surrounding said body and eraser, said ferrule having interior screw threads spaced from its ends and engaging the first mentioned screw threads so that the ferrule is adjustable longitudinally of the body to compensate for wear of the eraser, 25 said ferrule at one end having a portion longer than and covering the screw threaded portion of the body and spaced outwardly from the body, the other end portion of the body being interiorly smooth, the last mentioned portion and screw threads of the ferrule being spaced outwardly from the eraser.

In testimony whereof I have affixed my signature.

MAURICE ALLAND.
